UNITED STATES PATENT OFFICE.

THOMAS P. STRITTMATTER, OF JERMYN, PENNSYLVANIA.

DESIGN FOR AN ARTICLE OF MANUFACTURE.

54,147.

Specification for Design.

Patented Nov. 4, 1919.

Application filed May 1, 1919. Serial No. 294,094. Term of patent 3½ years.

To all whom it may concern:

Be it known that I, THOMAS P. STRITTMATTER, a citizen of the United States, residing at Jermyn, in the county of Lackawanna and State of Pennsylvania, have invented a new, original, and ornamental Design for an Article of Manufacture, of which the following is a specification, reference being had to the accompanying drawing, forming a part thereof.

The figure is a plan of a plate showing

my new design. This is not limited to a plate *per se*, but is adapted to be embodied in cut glass articles, namely, tumblers, plates, bowls, vases, trays, jars and any other suitable articles.

I claim:—

The ornamental design for an article of manufacture, as shown.

In testimony whereof, I have hereunto signed my name.

THOMAS P. STRITTMATTER.
